W. C. BUCKNAM & H. CAVE.

CUTTING TORCH.

APPLICATION FILED APR. 25, 1917.

Patented Jan. 22, 1918.

1,254,637.

UNITED STATES PATENT OFFICE.

WORTHY C. BUCKNAM, OF MARION, AND HENRY CAVE, OF ELIZABETH, NEW JERSEY,
ASSIGNORS TO DAVIS-BOURNONVILLE COMPANY, OF NEW YORK, N. Y., A CORPO-
RATION OF NEW YORK.

CUTTING-TORCH.

1,254,637.

Specification of Letters Patent. Patented Jan. 22, 1918.

Application filed April 25, 1917. Serial No. 164,325.

To all whom it may concern:

Be it known that we, WORTHY C. BUCK-
NAM and HENRY CAVE, citizens of the
United States, residing, respectively, at
5 Marion, Jersey City, in the county of Hudson
and State of New Jersey, and at Eliza-
beth, in the county of Union and State of
New Jersey, have invented a new and useful
10 Cutting-Torch, of which the following is a
specification.

This invention relates to hand cutting
torches, and its object is to provide a com-
pact and desirable construction whereby the
15 stream of cutting oxygen may be turned on
and off by the hand grasping the torch
quickly and conveniently, without disturb-
ing the aim. This is accomplished by a
20 combination involving a longitudinally mov-
ing valve at the rear part of the handle,
a trigger or finger-piece pivoted on a fixed
transverse axis forwardly of the valve at
25 the front of the grip portion of the handle,
and operating connections, such, for ex-
ample, as a toggle, adapted to be carried
past the center through rearward pressure
exerted upon the trigger so as to open and
lock the valve.

Other features and aspects of the invention
30 will be apparent to those skilled in the
art from a consideration of the following
description and the appended drawing illus-
trating the preferred embodiment and
wherein:

Figure 1 is a side elevation of the torch
35 with an intermediate portion of the pipes
and handle broken away and the trigger
being shown in the "closed" position; Fig.
2 is an enlarged fragmentary sectional view,
showing the trigger valve mechanism with
40 the valve open; Fig. 3 is a fragmentary ele-
vation looking at right angles to the plane
of Fig. 2; Fig. 4 is a cross-section on the
line 4—4 of Fig. 2; Fig. 5 is an elevation of
45 the connection block at the base of the
handle; and Fig. 6 is an enlarged cross-
section on the line 6—6 of Fig. 1.

The framework of the handle is consti-
tuted by a connection block 2 at the rear
end and three pipes 3, 4, and 5 extending
50 forward therefrom to a head 6, in which is
socketed a removable and interchangeable
tip 7. The conduit 3 is for cutting oxygen,
4 for heating oxygen, and 5 for the com-
bustible gas, which may be either acetylene
55 or hydrogen. The manner of leading the

gases through the tip and of mixing the
gases for the heating jet or jets may be
understood as being substantially similar to
that shown in Patent 1,044,741 of Novem-
60 ber 19, 1912. The major portion of the con-
nection block and a suitable extent of the
pipes are inclosed by a hollow cylindrical
casing 8, affording a grip for the hand of
the operator.

The connection block 2 has two connec-
tions 9 and 9^a, the former to receive the oxy-
gen hose and the latter the acetylene or
hydrogen hose. From the connection 9^a the
combustible gas passes directly into the con-
duit 5, its flow being regulable by a needle
65 valve 10. From the cavity 11, wherein the
connection 9 is screwed, the oxygen for the
heating mixture is by-passed by way of a
duct 12, to the chamber of a needle valve 13
and duct 14 to the pipe 4, the amount which
70 is allowed to flow through this pass being
regulable by the said valve. The portion
of the oxygen used for cutting leaves the
cavity 11 through a duct 15, by which it
75 enters a valve chamber 16, from which it
is allowed to flow by another duct 17 to the pipe 3.
The portion of the oxygen used for cutting leaves the
cavity 11 through a duct 15, by which it
80 enters a valve chamber 16, from which it
is allowed to flow by another duct 17 to the pipe 3.

The valve chamber 16 is formed by a
longitudinal cavity extending inward from
the rear face of the connection block, its
outer end being closed by a removable screw
85 plug 18. Forwardly of said plug the cham-
ber is of two diameters, the valve 19 being
slidable in the portion of larger diameter.
The entrance duct 15 opens into this larger
part of the chamber, while the exit duct 90
17 is drilled into the forward portion of
smaller diameter; between the two is a
shoulder 20 constituting a valve seat to co-
operate with the rounded end of the valve.
The said valve is made hollow, for the re-
95 ception of a helical extension spring 21,
which presses at opposite ends against the
plug and valve, so as to close the latter. A
stem 22 projecting forward from the plug,
serves as a central guide and support for the
100 spring. The valve is unseated by a rod 23,
disposed lengthwise within the grip casing 8
and slidable through a stuffing-box 24, with
its rear end reduced and loosely engaging
a small recess 25 in the front end of the 105
valve 19. This disconnection of the thrust
rod from the valve, which is seated by its
own spring, has a specific advantage, it may
be noted, in that it permits the valve cham-
ber cavity and the thrust rod opening to be 110

drilled from opposite sides of the block without resulting difficulty from possible disalignment.

A longitudinal slot 26 is provided in the forward or under side of the casing 8, just in advance of the portion gripped by the hand, and through this slot there projects a trigger-like finger-piece 27, the inner portion of which is pivoted on a fixed transverse axis, the pivot pin 28 being carried in this instance by a bracket piece 29 fixed to the front end closure 30 of the casing. The means whereby rearward swinging movement of the trigger opens and locks the valve 19 preferably comprises a toggle, of which one member is constituted by a portion of the trigger member itself. The other link 31 of the toggle is pivoted to the trigger-piece at 32 and to a slide 33 at the point 34. This slide is connected by a screw coupling 35 with the rod 23, of which it constitutes an extension, and its forward end is guided at 36 in the fixed part 30. The link 31 is slotted or bifurcated to receive the trigger member, and the slide 33 is slotted to accommodate both.

The trigger is operated to open the valve by a rearward pull of the forefinger. This straightens the toggle, pushing the rod 23 rearward and unseating the valve 19. The relations are such, as indicated, that the toggle is carried slightly past the line of centers, in which condition it is self-locking under the action of the spring 21, further movement of the toggle under the pressure of this spring being prevented by means of a suitable stop provision, such as the trigger striking against the rear end of the slot 26. In order to close the valve, all that is necessary is to push forward on the trigger sufficiently to break the toggle, whereupon the spring completes the movement and seats the valve.

While the preferred form of the device has been described in detail, it will be understood that numerous changes may be made in form and proportions, and through the substitution of equivalents, without departing from the substance of the invention.

50 What is claimed as new is:

1. In a cutting torch, the combination

with a handle having a grip with a fore and aft slot forwardly of the portion grasped by the hand and conduits for the gases including a cutting oxygen conduit, of a valve for 55 opening and closing said conduit inside the handle in rear of said slot, a trigger pivoted on a transverse axis inside the grip and having its finger portion projecting through said fore and aft slot for movement longitudinally of the grip, and connections inside the grip whereby rearward movement of the trigger unseats the valve.

2. In a cutting torch having a handle and conduits for the gases, the combination of a valve for opening and closing one of the conduits, a fore and aft operating trigger pivoted upon a fixed transverse axis in the handle, a longitudinal thrust member for opening the valve, and means operable by 70 the trigger and constructed to be carried rotatively past a center to operate said thrust member and to hold the same and the valve in the open condition.

3. In a cutting torch having a handle and conduits for the gases, the combination of a longitudinally movable valve in the handle for opening and closing the cutting oxygen conduit, a longitudinally movable trigger projecting from the handle, and a toggle 80 connection between the trigger and valve.

4. In a cutting torch having a handle and conduits for the gases, the combination of a valve mounted for movement lengthwise of the rear part of the handle to open and 85 close one of the conduits, a spring to seat the valve, a fore and aft movable finger-piece forwardly of the valve, and a longitudinally disposed toggle and rod inside the handle for opening the valve under the action of 90 the finger-piece.

5. In a cutting torch having a handle and conduits for the gases, the combination of a valve chamber in the rear part of the handle, a valve therein movable lengthwise of the 95 handle, a spring in the chamber for locking the valve, a thrust rod entering the chamber to open the valve, from which it is disconnected, and a finger-piece and self-locking toggle for operating said rod.

WORTHY C. BUCKNAM.
HENRY CAVE.
